UNITED STATES PATENT OFFICE.

JOSIAS TAYLER, OF NEW YORK, N. Y.

ROCK AND ORE CRUSHER.

SPECIFICATION forming part of Letters Patent No. 251,969, dated January 3, 1882.

Application filed April 6, 1881. (No model.)

To all whom it may concern:

Be it known that I, JOSIAS TAYLER, of the city of New York, in the county and State of New York, have invented a new and useful Improvement in Rock and Ore Crushers, of which the following is a full, clear, and accurate description, reference being had to the accompanying drawings, making a part of this specification, in which—

10 Figure 1 is a side elevation of the machine in working condition. Fig. 2 is a sectional side view, showing the jaws in perpendicular position. Fig. 3 is a sectional view, in perspective, of a detached jaw with face-plate in two sections. Fig. 4 is a perspective view of the lower section of a face-plate channeled longitudinally, as prepared for granulating. Fig. 5 is a side view of the jaws in position when drawn to one side by the extreme throw of the 15 crank, with dotted lines showing the relative change of position of the serrations or corrugations and hollows and rounds in the two jaws. Fig. 6 is a diagram showing the method of laying out the patterns for a pair of jaws, so that they will accomplish the purpose sought to be attained by the invention. Fig. 7 is a 20 vertical sectional view of a pair of granulating jaw-faces like the one shown in Fig. 4 in the position they occupy when ready for use.

25 30 The same letters represent the same parts in the different figures.

35 My invention relates to the reduction of rock, ore, or other similar substance by crushing, granulation, and pulverization, and seeks to accomplish the object by combined pressure and grinding or rubbing between metallic surfaces, uniting both methods in one machine, receiving the rock, quartz, ore, or other substance to be crushed in bulk and delivering it 40 in any desired condition of fineness.

45 I am aware that machines have been made for crushing rock and ore by means of iron corrugated jaws; but all of them are defective in many respects, and are so constructed as to be uncertain and irregular in their operations, and, when used for reducing ores to fine powder, are unreliable, not producing uniform results, and causing the machines to clog and otherwise render them impracticable.

50 I am also aware that crushers have been made with corrugated jaws suspended at the

top upon trunnions and moved or swung backward and forward by means of yokes in which the lower end of the jaws were confined and allowed to play loosely; but all such machines have failed to accomplish the purpose, and ore subjected to their action has had to be passed through clamps, heavy rollers, or other expensive devices before the ultimate object could be attained.

60 To overcome these defects and combine in one simple machine the crude crushing of the masses of rock, the regular granulation of the fragments, and the complete pulverization of the granules, when desired, I have constructed a machine which can be used for either or all the purposes named, can be readily adjusted so as to reduce the material to any desired fineness or mesh, can be operated with much less power than the crushers now in use, and 65 easily and cheaply repaired when worn by use so as to be as good as new.

70 To enable others skilled in the art to make and use my invention, I will proceed to describe the machine and the manner in which I 75 arrive at the desired result.

75 In the drawings which accompany this specification, A represents the sides of the framework, supported by the legs A' and tied together by the rods a, secured in their places by means of shoulders and nuts a'.

80 If desired, the shoulders may be dispensed with by passing the rods through hollow metallic pipes placed between the two side plates and cut of a length equal to the distance desired between the sides for the proper play of the jaws; or any other ordinary bracing may be employed.

85 B B represent jaws, of cast-iron or other proper metal, hung in the frame A A by means of the rods B', which pass through the frame, resting in bearings properly constructed therein, at sufficient distance apart to give the desired opening between the jaws to receive the rock or ore to be operated upon. These jaws 90 are so constructed that the bearings by means of which they are suspended in the frame are in the upper end of the jaws and in a horizontal line—that is, in a line parallel with the base of the machine—though, if desired, one jaw 95 may be lengthened above and the bearing for that jaw be arranged higher up than the other,

care being taken that the similarity of the lower portion of the two jaws shall be retained. The lower portion of each jaw is pierced with a hole, through which passes a rod, *b*, projecting 5 through a slot in the frame on each side of the machine. These rods are tied at the ends by means of the link *C*, arranged to play backward and forward on the outside of the frame, and held in place by a collar, *c*, at the end of 10 the rod. The link *C* is provided with a boxing and a wedge-shape key, *c'*, which is moved up and down and secured in position by means of the screws *b'*, for the purpose of setting the lower ends of the jaws in the desired degree 15 of proximity.

The jaws are provided with face-plates *D*, which present a serrated or corrugated surface on the upper portion. These serrations or corrugations are made to cross the jaws laterally, 20 the more effectually to engage the rock or ore and prevent its slipping or being forced upward by the action of the jaws when in motion and to hold it in position while being crushed by the grinding-pressure, as seen at *D'*.

25 The lower portion of the surface of the jaw-face is formed by two curved projections, *E F*, running across the face of the jaw, with a corresponding hollow, *G*, between them, so arranged that when the jaws are in perpendicular position, as seen in Fig. 1, the projecting curves at *E* and those at *F* will be in contact, or as near in contact as the setting of the link *C* will permit, while the corresponding hollows between them will be far enough asunder to 30 leave an open space or pocket between the projections above and below, as seen in Fig. 2.

The inner surface of the frame *A* is cut away opposite to the opening between the jaws, so as to admit a slide, *C'*, made of cast-iron or 40 other proper metal, which is placed in close proximity to the edge of the jaws and secured in such a manner that it can be removed at pleasure and replaced with a new one when worn or injured.

45 The face-plates may be cast in one piece, or may be divided into two pieces, so that one piece may be removed and replaced without disturbing the other.

The face-plates and side plates used in the 50 crusher are made of chilled iron or steel, so as to effectually resist the action of the rock and ore; but, if desired, they may be constructed of wrought-iron or any other proper metal.

The face-plates are secured in position by 55 means of bolts *e'* passing through the jaws, their heads being embedded in flanged grooves in the face-plates and made permanent by filling in with Babbitt metal or other suitable substance, and secured by nuts on the outside of 60 the jaw.

To prevent the strain which would come 65 upon the bolts *e'* by the peculiar action of the jaws, the face-plates are constructed with a flange on the back, which is fitted into a groove or channel cast in the jaw extending laterally across the jaw, as seen at *g*.

The jaws are operated by means of a crank-shaft, *H*, having bearings in the frame and provided with balance-wheels *H'* and pulley *h*, the crank being in the center between the sides of the frame and connected with the jaws by means of a pitman, *I*, one end of which is secured by a clamp, *J*, around the crank of the shaft and the other is received in a mortise or recess, *K*, made in the jaw behind and around the hole through which the rod *b* passes and connected to the jaw by passing the rod *b* through the hole in the jaw and through a corresponding hole or clamp, *L*, in the end of the pitman. 75

To secure a proper configuration of face-plate I place the jaw-patterns in position as hung upon their rods *B'* and tied at the bottom with the rods *b*, and made of such thickness that the two inner faces will come together in contact from the top to the bottom. I then mark off a space each side of the center line at the top equal to the throw of the crank for an opening to receive the material to be crushed. I then draw a line at right angles 90 with the center perpendicular line passing through the centers of the holes for receiving the rods *b*, and divide the center perpendicular line from this point upward and downward into spaces equal to the throw of the crank, 95 by parallel lines at right angles with the center perpendicular line. I then strike an arc of circle having a radius equal to the distance between the rods on which the jaws are suspended and the rods which serve to connect 100 the jaws at the bottom, the center of the circle being on the parallel line which passes through the center of the rods which connect the bottom of the jaws, and the periphery of the arc touching the center perpendicular line. This 105 are I extend above and below the line on which it is drawn a distance equal to the throw of the crank to be used in the machine. I then draw another arc precisely like the one described on the second parallel line below, the 110 lower extremity of this arc corresponding with the lower extremity of the jaw; or if the jaw is extended below I add a corresponding hollow. I then reverse the dividers, making the 115 center on the other side of the perpendicular line and on the parallel line intervening between the two arcs already drawn, and strike another arc between the two, connecting the lines above and below into one ogee-line, making a hollow between the two rounds, each hollow and each round being equal in extent to the throw of the crank. I then determine the 120 depth of the depression which I desire to make on the surface of the face-plates by means of serrations or corrugations, and proceed to serrate or curve the lines above the upper round and hollow, which are to mark the opening or mouth of the jaws, accordingly making each section of the line equal to the throw of the crank, and making the points or projections 125 of the serrations or corrugations on the two jaws on alternate parallel lines, so that as the 130

5 jaws approach each other the projections on one jaw will be opposed to the depressions on the other. The serrated or curved line is made continuous with the upper arc, and the jaw-patterns are then formed in accordance with the configuration indicated by the lines made as above set forth. The method of arriving at this configuration is fully explained by the diagram in the drawing Fig. 6.

10 When the jaws so constructed are placed in the crusher ready for use and hang perpendicular from the rods B', the two rounded projections, which represent arcs of circles or segments of cylinders or rolls across the face of the jaws, are in contact, and the hollow between them forms an elliptical chamber or pocket, closed above and below by the rounds, while the upper ends of the jaws are separated by a distance equal to the stroke of the 15 crank when in operation, which distance diminishes downward until the jaws come in contact at the upper rounds opposite the rods b.

I do not confine myself to this exact configuration of jaw, as the width and depth of the 20 serrations or corrugations may be varied to suit the kind of ore or rock to be crushed, or the nature of the result sought, and the radius of the circle on which the arcs are struck may be varied also to suit the work to be accomplished, so long as care is taken to make the 25 hollows and rounds arcs of circles and of uniform size and extent, so that the rounds will fit into the hollows and leave no opening for the escape of the material until it has reached the desired fineness, and will not jam so as to obstruct the operation of the machine. Neither 30 do I confine myself to two rounds and hollows on a jaw, as any greater or less number may be used if properly constructed; nor to any 35 specific width for the opening of the jaws at the top, as such opening may be made of any desired width at the top by so constructing the pattern, provided the jaws come in contact at the rounds on the lower portions.

40 In operation the machine, being ready for use, is adjusted by moving the wedges c' up and down, as may be required, by means of the screws b', which brings the rounds of the face-plates E E and F F into the desired proximity, 45 according to the fineness desired, and retains them there throughout the entire stroke of the crank. The power being applied by means of the pulley and the crusher set in motion, the lower ends of the jaws are moved backward 50 and forward by the action of the crank-shaft, thus swinging the jaws, and as each has its own independent center of revolution the faces oscillate backward and forward with a grinding motion. The rock or ore between them is seized 55 by the projections and held until crushed by the pressure, the fragments falling lower down into the opening, to be seized again by similar projections in its lower and narrower portion until the first round is reached. The ore 60 being now reduced into small particles is caught by the first round and ground to powder by

being rubbed and crushed against the surface of the corresponding hollow, and as the rounds E E and F F come in contact is forced down into the elliptical chamber or pocket to be 70 again caught by the other round and again ground and crushed against the surface of its corresponding hollow, and finally delivered from the machine at the bottom of the jaws in the desired condition.

75 It will be seen that each round on the surface of the face-plate has an upward and downward motion at each stroke of the crank, grinding the material against the hollow wall of the other face-plate, from which there is no escape, 80 thus making the action of these rounds and hollows equal at least to two pairs of rollers in efficiency, and in practice they seem to be far superior to two pairs of rollers.

85 Heretofore in the use of crushing-machines great difficulty has been experienced in the tendency to grind much of the stone to dust, while thin scales of considerable size would also pass through without crushing. This difficulty is effectually overcome by the longitudinally-serrated rounds and hollows shown at 90 Figs. 4 and 7, and used only for crushing and granulating and through which no thin scale can pass unbroken.

95 What I claim as new, and seek to secure by Letters Patent, is—

1. In a rock and ore crushing machine, a pair of serrated or corrugated oscillating jaws separated at the top, each suspended on an independent bearing and provided with one or more rounds, with corresponding hollows forming equal arcs of circles drawn on equal radii running laterally across the face of the jaws, as shown and described.

100 2. In a rock and ore crushing machine, oscillating jaws provided with face-plates in two sections, one of which sections on each jaw is serrated or corrugated and the other made with hollows and rounds of equal extent, and consisting of equal arcs of circles drawn on equal radii, as shown and described.

105 3. In a rock and ore crushing machine, jaws with serrated or corrugated faces, with each serration or corrugation running laterally across the jaws, equal in extent to the throw of the 110 crank which oscillates the jaws, the two lower projections and depressions consisting of equal arcs of circles drawn on equal radii, as herein shown and described.

115 4. In a rock and ore crushing machine, a pair of jaws the faces of which are provided at the lower extremities with one or more hollows and rounds formed of equal arcs of circles drawn on equal radii extending laterally across the jaws, and serrated or corrugated longitudinally, with the projections on one face opposed to the depressions on the other, as herein shown and described.

120 5. In a rock and ore crushing machine, the combination of two oscillating jaws suspended 125 apart at the top on independent bearings, and a link provided with boxes, sliding wedges,

and set-screws, for the purpose of adjusting and maintaining in position the lower ends of the jaws, as herein shown and described.

6. In a rock and ore crushing machine, the combination of a metallic frame with a pair of oscillating jaws suspended therein apart at the top, on independent bearings having face-plates attached by flanges, bolts, and screws, serrated or corrugated laterally across on the upper portion, and provided on the lower portion with hollows and rounds running across them, composed of equal arcs of circles drawn on equal radii and equal in extent to the throw of the crank, and links provided with boxes, wedges, 15 and set-screws, with rods connecting the lower ends of the jaws, and pitman, crank, shaft, pul-

ley, and balance-wheels, as herein shown and described.

7. In a rock and ore crushing machine, a pair of serrated or corrugated jaws diverging 20 from a given point upward in a hopper-like form and from the same point downward, having faces consisting of a series of hollows and rounds composed of equal arcs of circles drawn on equal radii and equal in extent to the throw 25 of the crank, having the projections of the rounds on the two faces parallel with each other, as herein shown and described.

JOSIAS TAYLER.
